SCAFFOLD CLAMP

Alex J. Sevachko, Youngstown, Ohio

Substitute for abandoned application Serial No. 314,609, October 14, 1952. This application May 28, 1958, Serial No. 742,457

1 Claim. (Cl. 144—297)

This application is a substitute for my abandoned application Serial No. 314,609, filed October 14, 1952.

This invention relates to a scaffolding and more particularly to a clamp enabling scaffolding to be formed from a plurality of 2 x 4's or the like.

The principal object of the invention is the provision of a clamp by which a plurality of 2 x 4's or similar pieces of lumber may be joined to form a unitary scaffold member.

A further object of the invention is the provision of a scaffold clamp that is simple and inexpensive in construction and readily applied to a plurality of pieces of lumber to temporarily join them in the formation of a scaffold member.

A still further object of the invention is the provision of a scaffold clamp that permits the use of lumber in scaffolding and its later reuse in a building.

A still further object of the invention is the provision of a scaffold clamp that holds the lumber used in a scaffold in side-by-side alignment and prevents the warping thereof which would otherwise render the lumber unsatisfactory for further use.

A still further object of the invention is the provision of a scaffold clamp that will hold several pieces of lumber such as 2 x 4's in an effective scaffold member such as a plank and prevent their accidental disengagement from the assembly thereby rendering the scaffold safe at all times.

The scaffold clamp shown and described herein is particularly useful in the formation of the plank-like members of scaffolds upon which workmen stand or walk. Several 2 x 4's, 2 x 6's or 2 x 8's which are commonly used in building constructions may be joined in side-by-side relation by the clamp disclosed herein to form an effective scaffold member without damaging the 2 x 4's in any way and at the same time hold them in straight position and thereby enable them to be used in the building construction after the scaffolding is torn down.

The scaffold clamp shown herein and two variations thereof serve to form a complete scaffold assembly both as to the running plank-like sections thereof, the corner sections and the end-to-end extensions.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

The invention is illustrated in the accompanying drawing wherein:

Figure 1 is a perspective view of an end portion of a scaffold member formed with the scaffold clamp.

Figure 2 is a composite view in perspective of the scaffold clamp shown in Figure 1.

2

Figure 3 is a top plan view of a scaffold corner showing a modified form of scaffold clamp joining the scaffold members to one another.

Figure 4 is a composite view in perspective of the modified scaffold clamp shown in Figure 3.

Figure 5 is a side view of a modified scaffold clamp holding two scaffold members in overlapping end-to-end relation.

By referring to the drawings and Figure 1 in particular it will be seen that a plurality of pieces of lumber such as 2 x 4's are shown in side-by-side assembly and generally indicated by the numeral 10 and form a plank-like scaffold member. The plurality of pieces of lumber 10 are held in side-by-side relation under tension 15 by a scaffold clamp comprising an elongated U-bolt 11 having a pair of oppositely disposed tubular members 12—12 positioned thereon and engaging the upper and lower surfaces of the pieces of lumber 10.

A pair of end plates 13—13 provided with spaced openings 14—14 are also engaged on the arms of the U-bolt 11 and butterfly nuts 15—15 are threadably engaged on threaded ends 16—16 of the U-bolt 11 to enable transverse tension to be exerted through the scaffold clamp on the several pieces of lumber 10 and thereby hold the 25 same in tight side-by-side relation.

It will be observed that the over-all length of the tubular members 12—12 is less than that of the over-all width of the several pieces of lumber 10. For example, five pieces of lumber comprising 2 x 4's having a 30 total width of less than twenty inches are effectively clamped together as shown in Figure 1 by the scaffold clamp when the tubular members 12—12 are 17½ inches long.

The same assembly will join three pieces of lumber of 35 2 x 6 dimension plus one 2 x 2 or two pieces of lumber 2 x 10 inches or two 2 x 8 pieces plus one 2 x 4. In other words, any combination of various standard commercial lumber sections may be effectively used to form a scaffold plank member of approximately 20 inches 40 width with the scaffold clamp, the principal clamping motion being sidewardly through the pieces and in some degree vertically due to the formation of the clamp itself.

Two obvious modifications of the clamp will enable it to be used in joining overlapping end sections of scaffolding members to form a right angle corner, as shown 45 in Figure 3, the modification of the clamp being illustrated in the perspective view of Figure 4 and wherein the U-bolt has the arm sections relatively further apart than the clamp used in Figures 1 and 2 and heretofore described.

In Figures 3 and 4 of the drawings the U-bolt is indicated by the numeral 17, the arms thereof are relatively far apart; for example, a distance sufficient to receive 50 between them two pieces of lumber each two inches thick in superimposed relation. The U-bolt 17 is of sufficient length to extend on a diagonal line across the corner as, for example, where five sections of 2 x 4's in each scaffold member are positioned in overlapping corner-like formation the 2 x 4's being indicated by the numerals 10 and 20, respectively.

It will be observed that triangular corner pieces 18—18 having spaced openings 19—19 therein are engageable upon the U-bolt 17, as best shown in Figure 3, so that butterfly nuts 21 may be used to clamp the assembly 65 together. The U-bolts are also provided with tubular members 22—22 which are placed one above and one below the assembled pieces of lumber 10 and 20. It will be observed that the tubular members 22—22 are shorter in length than the U-bolts 17 so that longitudinal clamping action is possible.

70 In Figure 5 two end sections of plank-like scaffold members may be joined to one another to form an

elongated scaffold member by the use of a clamp similar to that shown in Figures 3 and 4 of the drawings. In Figure 5 of the drawings two scaffold members are indicated by the numerals 23 and 24 and may obviously each comprise a plurality of 2 x 4's or similar sections of lumber and they are joined to one another in overlapping end-to-end position by a clamp comprising a U-bolt 25, oppositely disposed end plates 26 and butterfly nuts 27. Longitudinally extending tubular members 28-28 are provided and compare with the tubular members 22 and 12 heretofore referred to.

It will thus be seen that the scaffold clamp and two simple variations thereof may be used to form a complete scaffolding structure with respect to the longitudinal plank-like sections, the means for joining the sections to one another to form a right angle corner and means for joining them in end-to-end overlapping relation to form an extension as shown in Figure 5 of the drawings.

It will thus be seen that the scaffold clamp shown and described herein may be effectively used to form scaffold plank members from various sections of lumber and without injuring the same in any way and thereby enabling them to later be used in the construction and avoid the waste of utilizing lumber solely for scaffolding purposes.

The scaffold thus formed is safe and relatively light in weight and capable of being easily handled. The several pieces of lumber will not pull apart as in the case where

several pieces of lumber are nailed together in connection with wooden cross pieces of cleats as has heretofore been customary.

Having thus described my invention, what I claim is:

5 A scaffold clamp comprising an elongated U-bolt, a pair of tubular members positioned one on each of the arms of the U-bolt, said tubular members being shorter than said U-bolt, and a pair of apertured end plates which are triangular in cross section positioned in spaced relation to one another and movable along said U-bolt, the apertures in said end plates being spaced longitudinally thereof to enable the clamp to be positioned diagonally across superimposed pairs of groups of pieces of lumber with the sides of said end plates engaging the adjacent sides of said superimposed pairs of groups of pieces of lumber, and nuts threadably engaged on the ends of the arms of the U-bolt for moving one of said end plates relative to said U-bolt.
